UNITED STATES PATENT OFFICE.

LEVI H. SPRINGER, OF MAPLE CITY, KANSAS.

END-GATE FASTENER.

No. 859,141.

Specification of Letters Patent.

Patented July 2, 1907.

Application filed October 15, 1906. Serial No. 339,053.

To all whom it may concern:

Be it known that I, LEVI H. SPRINGER, a citizen of the United States, residing at Maple City, in the county of Cowley and State of Kansas, have invented 5 certain new and useful Improvements in End-Gate Fasteners, of which the following is a specification.

This invention consists of an improved form of end gate for wagons, and resides mainly in the provision of simple and novel locking means for securing 10 the end gate to the wagon body.

The invention also resides in novel details of construction, which will appear more fully hereinafter, and which will be finally claimed.

For a full description of the invention and the 15 merits thereof and also to acquire a knowledge of the details of construction of the means for effecting the result, reference is to be had to the following description and accompanying drawings, in which:

Figure 1 is a perspective view showing an end gate 20 embodying the invention applied to a wagon body. Fig. 2 is a top plan view partially broken away. Fig. 3 is a front elevation of the end gate alone. Fig. 4 is a vertical sectional view bringing out clearly the 25 engaging action of the catch on the end gate with the locking levers. Fig. 5 is a fragmentary perspective view of an end portion of one side of the wagon body, showing the members engaged by the locking extensions.

Corresponding and like parts are referred to in the 30 following description and indicated in all the views of the drawings by the same reference characters.

Specifically describing the invention, the numeral 1 designates the body of a wagon, the latter being of any conventional type. The end gate 2 may be 35 mounted at the rear or front end of the wagon, as desired and the locking mechanism for securing the end gate is mounted thereon.

The locking mechanism consists of two locking levers 3, the adjacent end portions of which are pivotally connected at 4 and the outer or opposite end portions of which are pivotally and slidingly connected with the outer ends of the gate 2, by means of pivot pins 5, which pass through slots 6 formed in said outer ends of the levers 3. The outer end of 45 each lever is formed with locking extensions 7 adapted to coöperate with the opposite sides of the wagon body to lock the end gate thereto, and said extensions are adapted to engage at the outer extremities thereof in recesses 8, which may be formed either in 50 the sides of the wagon body, as shown at one side of

Fig. 2, or said recesses 8 may be formed in a cleat 9, shown at the other side of Fig. 2. The latter construction is preferred, in that the side of the wagon body is not weakened by the forming of the recesses 8. The end gate when in position on the wagon body is 55 adapted to abut at its inner side, and at opposite ends with the cleat 9 above mentioned, and a second cleat 10, which is applied to the side of the wagon body opposite that to which the cleat 9 is secured. The recesses may be reinforced if desired by metal plates 60 11, attached to the cleat 9 in one instance, and to the opposite side of the wagon body in the other instance.

It will be understood that in the actual embodiment of the invention both of the sides of the body 1 will be 65 provided with the recesses 8, or will be provided with cleats such as shown at 9, either of which constructions may be utilized in the contemplation of the invention.

When the end gate 2 is locked in position on the wagon body 1, the locking levers 3 are in approximately 70 longitudinal alignment, with the extensions 7 coöperating with the wagon body in the manner hereinbefore described. The levers are held positively in such co-operation by means of a catch 12, which is secured to the end gate 2 intermediate of its ends, and which is 75 adapted to engage over the upper edge portion of one of the levers 3 to accomplish the desired result. The lower end of the catch 12 may be formed with an outstanding handle 13.

The specific connection between the locking levers 80 3 and the end gate include plates 14 secured to the outer side of the end gate at the ends thereof, and formed at the upper extremities with extensions 15, which are bent outwardly to overlap the levers 3 at the outer ends of the latter. The pivot pins 5 pass through the lower 85 ends of the extensions 15, the slots 6, and the plates 14.

To release the end gate it is only necessary to pull outwardly upon a handle 16 provided at the inner end of one of the levers 3 to thereby disengage the catch 12 from said levers and permit of upward movement of 90 the handle 16. The upward movement of the handle 16 causes pivotal movement of the levers 3 as well as a certain amount of sliding movement of said levers to remove the extensions 7 from the recesses 8, and the end gate may then be displaced from the wagon body. The 95 operation above described is reversed in attaching the end gate to the wagon body.

Having thus described the invention, what is claimed as new is:

In combination, a wagon body, an end gate therefor, 100

locking levers mounted on the outer side of the end gate and pivotally connected at adjacent ends, said locking levers being provided with slots between the ends thereof and being formed with locking extensions at the outer 5 ends to coöperate with the sides of the wagon body, a catch coöperating with the inner end of the wagon body, a catch levers to hold the same in coöperation with the wagon body, plates applied to the outer sides of the end gate and formed with extensions overlapping the locking levers 10 at the outer ends of the latter, and pivot pins passing

through the extensions of the plates, the slots of the locking levers, and the plates, for connecting the locking levers by a pin and slot connection with the end gate.

In testimony whereof I affix my signature in presence of two witnesses.

LEVI H. SPRINGER. [L. S.]
